UNITED STATES PATENT OFFICE.

JOHN MILHOLLAND, OF LEECHBURG, PENNSYLVANIA.

PAIR FURNACE.

1,427,009.

Specification of Letters Patent. Patented Aug. 22, 1922.

Application filed January 24, 1922. Serial No. 531,448.

To all whom it may concern:

Be it known that I, JOHN MILHOLLAND, a citizen of the United States, residing at Leechburg, in the county of Armstrong 5 and State of Pennsylvania, have invented new and useful Improvements in Pair Furnaces, of which the following is a specification.

This invention relates to furnaces, and 10 more particularly to what I term a pair furnace.

One of the main objects of the invention is to provide a furnace which is so constructed that the "pairs" or bars which are 15 heated preparatory to passing the same through the rolls in a rolling mill, are completely enclosed or enveloped by the products of combustion from the fire in the furnace so as to prevent oxidizing of the metal 20 and consequent scaling during the rolling operation. A further object is to provide a furnace of the character stated of comparatively simple construction and operation which may be erected at a reasonable cost. 25 Another object is to provide simple and efficient means for controlling the supply of steam and air to the fire. Further objects will appear from the detailed description.

In the drawings:—

30 Figure 1 is a side view of the furnace; Figure 2 is a horizontal sectional view; Figure 3 is a central vertical section; Figure 4 is a fragmentary side view showing the blowing nozzle as applied; 35 Figure 5 is a vertical section through the blowing nozzle;

Figure 6 is a section taken substantially on line 6—6 of Figure 5.

The furnace includes a casing 1 which 40 may be constructed of any suitable or preferred refractory material. This casing includes an ash pit 2 positioned beneath grate 3 in a fire box 4. A bridge wall 5 extends across the fire box in rear of grate 3 and is 45 reinforced by a central divider 6 extending from baffle 5 to a baffle wall 7 which extends from bottom 8 to top 9 of the furnace. This baffle wall is provided with two openings 10 positioned at opposite sides of member 6, these openings having their edges flush with the inner face of the bottom 8 of the furnace. A baffle wall 11 is provided adjacent to back wall 12 of the furnace, this baffle wall being provided with two openings or ports 13 corresponding to ports 10 55 but being spaced above the inner face of

the bottom wall. Back wall 12 is cut away to leave an escape opening 14 by means of which the products of combustion can escape into a sheet furnace positioned in the rear 60 of casing 1.

One side wall 1^a of casing 1 is provided with an opening 15 communicating with the fire box 4, this opening being normally closed by a door 16 slideable in guide strips 65 17, any suitable or preferred means being provided for operating this door, such as a cable 18 secured at one end to door 16 and passed over guide pulleys 19, a counter-weight 20 being secured on the other end of 70 this cable. Wall 1^a is further provided with two openings 21 communicating with the space between bridges 7 and 11, these openings being normally closed by doors 16^a mounted and operated in the same manner as door 16. In practice the "pairs" to be heated are placed in the furnace through the door adjacent to bridge 7 and, after being heated to the required temperature, are stacked adjacent to baffle wall 11 so as to be 75 readily removed through the other opening 21. While the pairs are in the furnace they are completely surrounded and enveloped by the products of combustion which flow across the lower portion of the space between baffles 7 and 11, as indicated in Figure 3, the carbon dioxide and other gases which are produced by combustion surrounding and enveloping the pairs so as to prevent access of air to the same when either 80 of the doors 16^a is opened. This prevents oxidizing of the pairs and thus eliminates scaling which occurs when the pairs are heated in furnaces of the type now commonly used in which air can enter the furnace and come into contact with the pairs 85 when the furnace door is opened.

To assist in the operation of the furnace I provide a nozzle 22 which fits into an elbow 23 secured through side wall 1^b of the casing 100 1 beneath grate 3. A tapered valve plug 24 is rotatably mounted in the upper portion of a valve casing 25 from which nozzle 22 extends, and is provided with two bores 26 and 27 disposed to be turned into alignment 105 with corresponding bores 28 and 28^a, and 29 and 29^a, respectively, formed in casing 25. An air supply tube 30^a is secured in bore 29^a and an air discharge tube 30 is secured in bore 29. A steam supply tube 31^a is secured 110 in bore 28^a, and bore 28 communicates with space 31 formed between tube 30 and nozzle

22 and providing a discharge space for the steam. Steam and air are simultaneously supplied by means of tubes 31^a and 30^a, and associated parts, to elbow 23 and are injected into the fire box beneath grate 3 for producing more complete combustion which results in the production of intense heat capable of heating the pairs in the space between bridges 7 and 11, the products of 10 combustion completely surrounding and enveloping the pairs in the manner and for the purpose above stated. A hand wheel 32 is secured on stem 33 of valve plug 24 so that by turning this hand wheel the supply 15 of air and steam to elbow 23 may be cut off simultaneously thus avoiding any chance of accident such as is apt to occur where the air and the steam are controlled separately, and giving a more direct control over the 20 supply of air and steam.

What I claim is:—

1. In a pair furnace, a casing provided at one end with a fire box, baffles extending across said casing adjacent to each end thereof, the baffle adjacent to the fire box being provided with ports positioned closely adjacent to the bottom of the casing and the baffle remote from the fire box being provided with ports spaced above the bottom 30 of the casing.

2. In a pair furnace, a casing including

a fire box, a bridge positioned at the inner side of the fire box, a baffle positioned adjacent to said bridge and in spaced relation thereto and extending throughout the cross-area of the casing, said baffle being provided in its lower portion with ports adjacent to the bottom of the casing, and a baffle positioned remote from the first mentioned baffle and extending throughout the cross-area 40 of the casing, the second mentioned bridge being provided in its lower portion with ports spaced above the bottom of the casing.

3. In a pair furnace, a casing provided with a fire box at one end, a bridge adjacent 45 to the inner side of said fire box, a baffle extending throughout the cross-area of the casing and positioned adjacent to said bridge, said baffle being provided in its lower portion with ports closely adjacent to the bottom of the casing, a divider extending from the bridge to the baffle and positioned midway between said ports, and a second baffle positioned adjacent to the other end of the casing and extending throughout the cross-area thereof, said second baffle being provided with ports spaced above the bottom 50 of said casing.

In testimony whereof I affix my signature.

JOHN MILHOLLAND.
